UNITED STATES PATENT OFFICE.

JACOB S. JAMMER, OF NEW YORK, N. Y., ASSIGNOR TO WESTERN ELECTRIC COMPANY,
INCORPORATED, OF NEW YORK, N. Y., A CORPORATION OF NEW YORK.

CARRIER-WAVE SIGNALING SYSTEM.

Application filed November 3, 1924. Serial No. 747,513.

This invention relates to carrier wave signaling systems and more particularly to terminal arrangements for associating the sending and receiving branches of one or 5 more two-way carrier wave signaling circuits with a common transmitting line or medium.

One object of the invention is to provide 10 circuit arrangements for such a system, whether of the single or multiple channel type, which combines relative great efficiency, simplicity, and low cost with adequate protection against the various types 15 of interference which are incidental to the operation of such systems.

In a common case, justification for the installation of a carrier wave signaling system, and particularly that type which utilizes the transmission of high frequency carrier waves over wires, and hereinafter called 20 a carrier current signaling system, arises under conditions where the traffic over an existing low frequency system is such that prospective increases in traffic cannot be provided for by a mere proportional extension 25 of its facilities, but would require a more or less complete reorganization of the system. The situation can frequently be better and more economically taken care of by 30 the installation of a carrier current system. If there is no existing signaling system, the prospective traffic must be sufficient to 35 justify the considerable first cost and operating cost for such type of carrier wave system or of a carrier wave signaling system of the other common type in which etheric space instead of a conductor is used as the transmission medium.

A carrier wave signaling system and especially one associated with a line wire has 40 usually connoted a multiplex system, and properly so; in other words, the use of a single channel system ("single channel" as used here and throughout the application is 45 intended to define a two-way circuit, that is, a complete conversational unit) has required the use of circuits and devices that could be used in common for a plurality of such single channel circuits, so that considerations of economy has urged the unitary 50 use of a plurality of such circuits in a single multiplex system. The practical result has been that the installation of carrier wave systems has had to be postponed to the time

when the installation of a multiplex system 55 would be justified.

A further object of this invention is to make the economy and other advantages of carrier wave signaling systems realizable in smaller units than has heretofore been possible, and specifically to provide a single channel carrier wave signaling system in 60 which the efficiency of operation, first cost, simplicity, etc., approximates that of an equivalent single channel circuit comprised 65 within a multiplex carrier current system.

Another object is to provide a single channel system which satisfies the requirements of the above object and which is 70 adaptable to extension into an equally efficient multiplex system and particularly into such a system having frequencies in each direction comprised within an individual band, that is, a system using the "group" 75 frequency arrangement.

A still further object is to provide a multiplex carrier wave signaling system having simple means insuring that the spacing between the higher frequencies is greater 80 than that between the lower frequencies, so as to approximate the often desirable condition of progressively increasing frequencies through the transmission range, the frequencies increasing by equal percentage increments.

In the preferred arrangement of the invention as embodied in a multiplex system, a plurality of two-way carrier current communication channels having the unmodulated carrier suppressed are associated with 90 a common transmitting circuit between opposite termini, the individual two-way channels, and the portions of said channels used for each direction of transmission, being distinguished from each other by the 95 use of different frequency ranges. Each two-way circuit (channel) utilizes at each terminus a single translating device which combines the functions of an oscillator, balanced modulator and balanced demodulator. The carrier frequencies for each two-way circuit are the same for the two directions. However, to provide for transmission of different frequencies in the two portions of 100 each two-way channel, such as is required for the individualization of the functions occurring in such portions, the modulated side bands used in one direction are of the type 105

represented by $p \pm q$, in which p is the carrier frequency, q is the modulating frequency and the symbol $\pm$ indicates that the sum, the difference or both the sum and difference, and modulated waves having frequencies indicated by $2p \pm q$ are used for the opposite direction. The translating devices at the termini accordingly utilize the same basic carrier frequencies for modulation but transmit different selected modulated products and correspondingly when they are being used as demodulators.

One way in which side bands of the type $2p \pm q$ may be produced in a single translating device is by the process known as third order modulation. The corresponding process of reproducing q from such side bands is known as third order demodulation. In order to use these processes in accordance with this invention, the translating device at one terminus is adaptable to produce, by modulation, second order side bands of the frequency $p \pm q$ and also to act on received third order side bands of the frequency $2p \pm q$ to reproduce by third order demodulation the modulating frequency q . The translating device at the other terminus functions in the same way except that the modulating and demodulating processes are accomplished with reference to the complementary frequencies, since the received frequencies at one terminus corresponds to the transmitted frequency at the other terminus.

The use of a single channel of the multiplex system described above, insures the most efficient use of material for the required functions and makes possible the practical realization of the benefits of multiplex carrier current transmission in a single channel unit. On account of the feature of using widely different order transmissions for different directions, such a single channel circuit may be considered as being on a group frequency basis. Such a single channel system is accordingly adaptable to extension into a multiplex system using the group frequency arrangement. In extending the system in this manner, the additional side bands transmitted from one terminus will be comprised within the frequency interval between the carrier frequency of the first mentioned circuit and the double carrier frequency corresponding to its one-way return channel.

A particular advantage of such a resulting multiplex system not realized, for example, in another type of system using the group frequency arrangement in which the various carrier frequencies both for transmission and reception at a terminus are derived by harmonic generation from a single base frequency, is the resulting increased spacing between the frequency corresponding to the one-way channels having the higher frequencies. For example, where third

order side bands are transmitted in one direction and second order in the other, the spacing between the former frequencies, that is, the higher ones, will be twice that of the frequencies in the latter, the lower frequencies. The system accordingly provides in a simple manner a spacing arrangement which approximates the desired ideal in which the spacings are progressively increased by equal percentage increments, such variation of spacing being necessary in order to make the most efficient use of the frequency selecting means in the system.

The invention both as to its principles and its practical embodiment will be better understood by reference to the following detail description taken with the accompanying drawing in which:

Fig. 1 illustrates diagrammatically a complete single channel system adaptable to extension into a multiple channel system of the group frequency type the terminal portions of additional channels of the system as extended being indicated;

Fig. 2 illustrates in detail one form of the circuit OMDW and OMDE of Fig. 1 which embodies a common translating device which functions as a balanced self-oscillating modulator-demodulator and

Fig. 3 illustrates in detail a circuit alternative to that of Fig. 2 which utilizes a separate local carrier source.

In the description which follows the elements of the system will be identified, as far as practically possible, by designations which are suggestive of their respective functions. For example, in the drawing the labels OMDW, TFW, RFW and HFW will be used to identify respectively an oscillator-modulator-demodulator used at the western terminus of the system, a filter used for transmission at the western terminus, a filter used for reception at the western terminus and a high frequency band pass filter at the western terminus. Elements which are duplicates of each other functionally, so as to require the use of the same literal designations but which are differently located or utilize different frequencies, will be distinguished by the use of different subscripts.

Referring to Fig. 1 the circuits at the left of this figure are related to one terminus, designated for convenience as the west, of a single channel or multiplex system and the circuits at the right of the figure are correspondingly related to the other, the east, terminus of the system. The circuits at the respective stations are each connected to the conductive transmission path 1. The system is composed for simultaneous low frequency and carrier current communication. This is accomplished by "carrier composite sets" comprising low frequency filters LFW and LFE and carrier frequency filters HFW and HFE. The first two are positioned in

the low frequency telegraph or telephone branch, and the last two in the carrier current branch, of the transmission line. These filters accordingly effectually separate the 5 currents corresponding to the frequencies used in these respective types of transmission. Obviously, the system could be used for carrier current transmission alone, in which case these filters could be dispensed 10 with.

One complete single channel system is disclosed. This channel comprises the following elements which may function in like sequence in a two-way conversation initiated 15 at the west terminus; low frequency line 2, oscillator-modulator-demodulator OMDW, transmission band pass filter $T_1 FW$, grouping transmission band pass filter TFW, the high-pass filter HFW of the composite set, 20 the common transmission line 1, the high pass filter HFE of the composite set at the east terminus, the grouping receiving filter RFE, the receiving band pass filter $R_1 FE$, the oscillator - modulator - demodulator 25 OMDE and the low frequency line 3.

Let it be assumed that second order modulator side bands, which may be represented as above by $p \pm q$, are used for transmission east. The operation of this channel is as 30 follows: The low frequency modulating currents in line 2, which for example may be connected to a central telephone office, modulate a carrier current in circuit OMDW, which as will appear more fully from the description of Figs. 2 and 3, may embody a 35 unitary balanced self-oscillating modulator-demodulator or a combination of a balanced modulator-demodulator and a separate local source. The resultant modulated side bands 40 of frequencies $p \pm q$ are transmitted through filters $T_1 FW$, TFW and HFW to line 1 and then to the east terminus where they are transmitted through filters HFE, RFE and $R_1 FE$ to circuit OMDE which may be 45 similar to circuit OMDW where they are combined by demodulation with a locally generated carrier wave to reproduce the modulating wave q , which is transmitted over low frequency line 3. For the opposite 50 direction of transmission, a similar sequence of operations occurs. However, for this case the circuit OMDE functions as a modulator instead of as a demodulator. Correspondingly the circuit OMDW functions as a demodulator instead of as a modulator. Further, for this direction of transmission, side bands of the frequency $2p \pm q$ are used. These side bands are accordingly produced 55 by modulation in the circuit OMDE and are impressed upon circuit OMDW to reproduce by demodulation the modulating wave q .

There are at least two ways in which side bands of frequencies $2p \pm q$ may be produced. For example, it may result from 60 third order modulation or demodulation.

This is a process in which the curved grid-potential-plate-current characteristic of the modulator or demodulator, as the case may be, is utilized according to a method entirely analogous to that of the usual method 70 of modulation, here designated second order, except that it utilizes the odd power instead of the even power terms in the general equation of this curve.

The following is a theoretical demonstration of third order modulation or demodulation. It must necessarily involve much of the basic theory that underlies modulation generally, including second order modulation. 75

In order to prove that various multiple order side bands occur and to determine the extent to which they occur, an extension of the method of analysis used in U. S. patent 80 to Carson, Serial No. 1,449,382, issued March 27, 1923, will be used.

According to that method a statement of the current (or potential) resulting from modulation is obtained by substituting in the general equation of the type 85

$$y = ax + bx^2 + cx^3$$

values of the simultaneously impressed currents (or potentials). Suppose that the input currents are $P \cos p_1 t$ and $Q \cos q_1 t$, in 90 which p_1 and q_1 , respectively, equal $2\pi p$ and $2\pi q$, so that $x = P \cos p_1 t + Q \cos q_1 t$. (No material change would result if an initial phase angle between the two impressed waves were assumed). By substituting this 95 value of x , the first term ax yields merely amplified waves of the impressed frequencies p and q . The term bx^2 yields waves of frequencies $2p$, $2q$, and $p \pm q$, as is well known. The second order side bands $p \pm q$ 100 result from the trigonometric expansion of the product $bPQ \cos p_1 t \cos q_1 t$. The harmonic frequencies $2p$ and $2q$ result from trigonometric expansions of, respectively, $bP^2 \cos^2 p_1 t$ and $bQ^2 \cos^2 q_1 t$.

If each of the remaining terms of the 110 general equation are algebraically expanded by the binomial theorem, it will be found that the expanded equation comprises terms in powers of $\cos p_1 t$ and $\cos q_1 t$, and terms which contain the product $\cos p_1 t \cos q_1 t$ as a factor. The first two obviously yield waves whose frequencies are, respectively, harmonics of p and q . The last obviously yields combination frequency waves, that 115 is, side bands. Considering these product terms it will be found that those contained in the expansions of the odd power terms (except the linear term) of the general equation produce odd order side bands. 120

Specifically, it will be found that alternate terms, beginning with the second, of the expansion of each of these odd power terms of the general equation have even powers of cosine $p_1 t$ and odd powers of cosine $q_1 t$. These terms in their regular 125

order, up to and including those for the seventh power term of the general equation, are as follows, retaining only the necessary coefficients:

$$\begin{aligned}
 5 & P^2Q \cos^2 p_1 t \cos q_1 t \\
 & P^4Q \cos^4 p_1 t \cos q_1 t \\
 & P^2Q^3 \cos^4 p_1 t \cos^3 q_1 t \quad (1) \\
 & P^6Q \cos^6 p_1 t \cos q_1 t \\
 10 & P^4Q^3 \cos^4 p_1 t \cos^3 q_1 t \\
 & P^2Q^5 \cos^2 p_1 t \cos^5 q_1 t
 \end{aligned}$$

The frequency determining quantities in these terms are each of the form $\cos^2 p_1 t \cos q_1 t$ times one or more cosine squared quantities.

Since $\cos^2 \alpha = \frac{1}{2} + \frac{1}{2} \cos 2\alpha$, the development of the portion $\cos^2 p_1 t \cos q_1 t$ contains the term $\frac{1}{2} \cos^2 p_1 t \cos q_1 t$. The product of this term with the development of the remaining cosine squared quantities results in a term made up of the product of this term and $\frac{1}{2}$. Accordingly, the development of each of the terms in (1) contains a term of the form $\cos 2p_1 t \cos q_1 t$. This form is similar to the form $\cos p_1 t \cos q_1 t$ and in an analogous manner yields upper and lower side bands of $2p_1$. This demonstrates that the terms in (1) each denotes a third order side band of the type $2p_1 \pm q_1$.

30. The amplitudes of each of the resultant upper and lower side bands may accordingly be expressed as a series, the terms of which are proportional to P^2Q , P^4Q , P^6Q , P^2Q^3 , P^4Q^3 , P^2Q^5 . In order that the side band components may have amplitudes such that the modulating wave which is reproduced by demodulation may be the same as the original modulating wave used in the modulating operation, the sum of these coefficients should be linear as to the quantity Q . In this connection it should be noted that such sum would be linear in Q except for the last three coefficients which contain higher powers of Q . However, these last coefficients correspond to the higher power terms of the general equation. In general the coefficients decrease in magnitude as the power of the terms of the general equation increases. In fact the characteristic curve

50. may be caused to be substantially "cubic", so that substantially only the coefficients P^2Q which is linear in Q is present. Consequently, for practical purposes, the sum of these coefficients may be made linear in Q . 55. Any distortion due to the presence of coefficients containing higher powers of Q may be minimized by making P large as compared with Q .

60. Although third order modulation may be used, as described, the method of the invention resides in the production of side bands having a certain frequency characteristic regardless of the particular physical operation by which they are produced. Another method of modulation and demodula-

tion which can equally well be used to produce these side bands in the translating device shown, is that which may be denominated "cascade modulation" or "second order modulation on the double carrier". In this type of modulation the first even harmonic of the carrier is produced by distortion accompanying the oscillatory function of the device, the resultant double frequency carrier resulting from a principle similar in all theoretical aspects to second order modulation. The side bands of frequency $2p \pm q$, are then produced by second order modulation involving the modulating wave and the wave of the double carrier frequency.

As a practical matter, the two sets of operations may go on simultaneously so that it is ordinarily difficult, or impossible, in a specific case to determine the relative parts played by each of them, although by special design one type of modulation can be caused to result, to the substantial exclusion of the other.

It should be noted that for either method of modulation, the translating devices oscillate, at least in their fundamental modes, at the same frequency. If third order modulation is used to the exclusion of cascade modulation, only third order demodulation or cascade demodulation may be used at the other station, since third order modulation per se is not attended by the production of a double carrier frequency component, which, if present and if transmitted, could be utilized at the other station in second order demodulation to reproduce the modulating wave. If cascade modulation is used and the double frequency carrier is transmitted, a simple type of second order demodulator, not requiring the use of locally produced oscillations, could be used at the other station. In the operation of the specific type of circuit disclosed, it is contemplated that third order modulation and demodulation will be used, the original carrier p being suppressed by the balanced type arrangement, for reasons of economy of energy and of frequency range utilized.

By reason of the fact that in the operation of the single channel system as described, widely different frequencies are used for opposite direction of transmission, such a system can be considered as being on a group frequency basis. This means that the system is adaptable to extension into a multiplex system merely by adding other similar single channel circuits, the frequencies transmitted in one direction being adjacent to that of the corresponding carrier of the single channel system described and the third order side bands of the additional channels used for transmission in the opposite direction being similarly arranged adjacent to the corresponding third order side bands in such single channel system. Each

of these additional single channel circuits are connected to the system through a set of filters such as T_2FW , R_2FW , T_2FE and R_2FE , each pair of filters at a station such as T_2FW and R_2FW being connected to a translating device similar to OMDW or OMDE which in turn is similarly related to an individual low frequency circuit. Fig. 1 discloses a multiplex system having three such single channel circuits.

In a typical multiplex system combining three such single channel circuits the carrier frequency from west to east may be 7,000 cycles, 10,000 cycles and 13,000 cycles, the corresponding double carrier frequencies for the opposite direction being accordingly 14,000 cycles, 20,000 cycles and 26,000 cycles. If these particular frequencies are used there is no overlapping of the carrier ranges for the two directions. However, in order to prevent an overlapping of the side bands at the inner boundaries of the two groups, it is necessary to transmit only the upper side bands from east to west and only the lower side bands from west to east. Other arrangements of carrier frequencies than those mentioned will obviously be suggested, in some of which it would not be necessary to transmit only one side band, although as a practical matter it is always in the interest of economy of energy and of frequency range to do so.

Grouping filters TFW, RFW, TFE and RFE can be dispensed with. However, they are almost universally used in multiplex systems of the group frequency type, their use being justified on account of their contribution to the ease of impedance matching in various parts of the system, which matching is necessary for the most efficient transfer of energy between sections of the circuit having different impedances. The filters HFW and HFE may be similarly dispensed with on occasion, although their use is justified by reasons similar to those above. The group frequency arrangement is only one of several alternative frequency arrangements that are commonly used in carrier current communication. When such an arrangement can be used, balancing circuits can be dispensed with entirely and frequency selection alone relied upon to separate the frequencies of the various channels, as disclosed in this figure. This arrangement is used in practice where, on account of the proximity of transmitting and receiving circuits and the widely different orders of energy involved in transmission and reception, balance cannot be made sufficiently accurate to discriminate between the oppositely directed transmissions. The interference produced by the lack of discrimination between these transmissions is known as "cross-talk in opposite directions" as distinguished from the ordinary type of cross-

talk which measures the interference between receiving circuits where there is insufficient discrimination between a wave intended for a particular receiving circuit and that intended for an adjacent receiving circuit, and as distinguished from side tone, which measures the interference between the transmitting portion of a two-way circuit and the receiving portion of the same. In situations where multiplex carrier systems are now justified, it is found that the group frequency arrangement is ordinarily preferable to these alternatives.

This invention as so far disclosed therefore provides a single channel carrier current system which is readily capable of extension into a preferred form of multiplex system and one which embodies a frequency arrangement which approaches more nearly to the ideal in which the frequency spacing progressively increases by equal percentage increments than other multiplex systems of comparable simplicity or first cost. As will appear from the following detailed description of the circuits OMDW and OMDE, it will also be obvious that, by reason of the economies effected by the use of elements having combination functions, the single channel system is remarkably simple, efficient and inexpensive. The invention as a whole, accordingly, to a great extent provides means for realizing the economies of carrier wave communication for a wide range of traffic conditions.

It should be noted that in transmission from the west station any unmodulated carrier that is not completely balanced out can be suppressed only by adjusting the cut-off frequencies of the filters TFW, etc., so that the filters discriminate against this frequency p . It has been found to be a difficult matter to suppress this carrier without at the same time distorting the side bands. This difficulty of course is not specific to the system illustrated, but is common to all suppressed carrier systems using second order modulation. The use of a transmission of the type $2p \pm q$, as in transmission from the east station in the system illustrated completely avoids this difficulty on account of the different order of spacing of the carrier p and the side bands $2p \pm q$. As a result it is possible to extend the transmission range of the filters to transmit all the side band frequencies equally, with attendant avoidance of distortion of boundary side band frequencies.

Fig. 2 illustrates the details of one example of the translating device OMDW or OMDE of Fig. 1. This translating circuit consists of a self-oscillatory-modulator-demodulator arranged to oscillate at the carrier frequency p that is used for both directions of transmission. It functions as a modulator to combine this frequency with a

wave having the modulating frequencies q to produce side bands of frequencies $p \pm q$ or $2p \pm q$, depending on the particular one of the two translating devices that is referred to. It correspondingly functions as a demodulator to combine the incoming side bands, whether characterized by a fixed frequency p or $2p$, with the carrier p , to reproduce the modulating wave q . As has been pointed out in the description of Fig. 1, the modulating and demodulating functions involving the fixed frequency $2p$ may result from either or both of two quite dissimilar physical operations. However, in the particular example illustrated in Fig. 2, by reason of the balanced arrangement of circuits, the modulation must be of an even order such as "second order modulation on the double carrier" as above described that is, although third order side bands can be produced in the output circuits of the individual tubes, they cannot be transmitted to the circuit related in common to both tubes. In addition to its functions as pointed out above, the translating device also, by reason of this use of balanced arrangement of circuits, insures that the output currents do not contain the unmodulated carrier component. If the balance were not complete, if there were any dissymmetry of the tubes or their associated circuits, or if a single tube were used, third order modulation or demodulation could be used, although, of course, with a sacrifice of the advantage of completely suppressing the unmodulated carrier component.

The common translating circuit is shown as comprising a balanced vacuum tube circuit including the two vacuum discharge tubes 4 and 5 which may be of the usual cathode-grid-anode type. The cathodes of these tubes are connected together and to the midpoint of the secondary of the input transformer 6, the grids of the tubes being connected to the respective opposite terminals of the secondary. The cathodes are also connected, through tuned feed-back circuit 7 and through circuit 8, the function of which will be described later, to the midpoint of the primary of the output transformer 9, and thence through the two halves of this primary to the anodes of the respective tubes. Space current is supplied to these anodes from direct current source 12, through circuit 8 and the two halves of the primary of transformer 9. Condenser 10 and high frequency choke 11 insure that the space current and the high frequency feed-back current are confined to their proper paths. The common portion of the grid circuits included between the cathodes and the secondary of input transformer 6 contains a secondary winding 13, coupling the tuned circuit 7 to the common input circuits of the balanced arrangement, and the

secondary winding 14 which similarly couples circuit 15, the function of which will be described later, to this common input circuit. This common portion of the grid circuits may also include grid polarizing battery 16, the grid polarizing potential being impressed on the respective grids through secondaries 13 and 14 and the two halves of the secondary winding of transformer 6. A grid resistance 17 may be inserted, if desired, in each of these grid polarizing paths. The circuit 15 provides a path whereby the incoming modulated side bands are impressed on the translating devices. Circuit 8 similarly provides a path for impressing the resultant demodulated low frequency currents on the low frequency line 2. Filter 18 in this circuit insures that the current thus impressed will not contain demodulated components other than that corresponding to the modulating frequency q . Since this filter is of the low pass type, circuit 8 provides a conductive path for the space current.

It is a characteristic of a properly balanced circuit of the type illustrated in this figure that the output coil constituted by the primary winding of transformer 9 and the input coil constituted by the secondary of transformer 6 are balanced as to voltages applied to the common portion of the grid circuits. Consequently the circuits connected to the secondary of transformer 9 and the primary of transformer 6 are balanced as to these voltages. However, voltage variations impressed on the common portion of the grid circuits are repeated in amplified form into the two anode branches which includes the common portion comprising tuned circuit 7 and circuit 8 and the portions individual to the two anodes comprising the respective halves of the primary winding of transformer 9. By tuning the circuit 7 to the desired carrier frequency, the translating circuit may therefore be caused to oscillate independently at this frequency, since the output energy in the tuned circuit is returned in part to the input circuits, where it is again amplified. Since the path which the oscillations follow is, as above stated, neutral with respect to the input and output circuits connected to transformers 6 and 9, the waves locally generated are confined to the translating circuit and are therefore prevented from passing into either of these circuits.

The operation of the translating circuit as a modulator and demodulator will be clear from the following description of the path taken by currents in the course of transmission and reception, with relation to the path of the oscillating current.

Modulating currents of frequencies q (if telephone communication is assumed or of a single frequency if telegraph communication

is assumed) from low frequency circuit 2, are impressed on the primary winding of transformer 6 and, on account of the connection of the secondary to the grids, cause the potentials of the grids of tubes 4 and 5 to vary in an opposite manner to each other, to produce complementary impedance variations in the anode-cathode paths of these tubes. In this manner, the translating circuit is unbalanced to an extent dependent on the amplitude of the impressed potentials and the modulating waves are accordingly transmitted to the output circuit connected to transformer 9 as variations in the amplitude of the high frequency current produced by the translating device by reason of its oscillatory function, which high frequency currents themselves are balanced so that they do not appear in the output circuit. As long as controlling currents are impressed on the device upper and lower modulated side bands of a high frequency p or $2p$ are produced in the output circuit. When the device functions as a second order modulator, these modulated side bands will have the frequencies $p \pm q$. If the device functions as a cascade modulator the side bands will have the frequencies $2p \pm q$ and similarly if, by reason of an incomplete balance or the use of only one of the tubes, third order side bands may be produced. Other components of modulation, and the amplified modulating currents, appear in the output circuit of the device but are prevented from flowing in the transmitting circuit 1 by the high pass filters between the device and said circuit and illustrated in Fig. 1.

Incoming side bands which pass through the high frequency receiving filters illustrated in Fig. 1 are impressed through circuit 15 on the common portions of the grid circuits. These side bands are combined with the carrier frequency p in the same manner as if currents of frequency p were separately impressed on the common portion of the circuit. Although the individual portions of the output circuits of the two tubes are balanced with respect to any potentials impressed on these common portions of the grid circuits, the common portions of the output circuits are not similarly balanced. Therefore, combination frequency components resulting from interaction of the carrier frequency p and the side band frequencies in the tubes appear in this common portion which includes circuit 8. By reason of the fact, and to the extent that, the individual portions of the output circuit are balanced with respect to the common portion, frequencies impressed on the common portion of the grid circuits and their combinations are therefore superposed in additive relation in circuit 8. Filter 18 suppresses all of these components except the desired reproduced modulating wave of frequency q and transmits this component to circuit 2. Outgoing modulating currents which flow through filter 18 are not transmitted to the circuits connected to the secondary of transformer 9 on account of the balanced relation of the output circuits of the tubes. By reason of the unilaterally conducting properties of the tubes, these currents are prevented from flowing to the input circuits of the tubes to set up a singling condition of the circuits related to the translating device.

It should be noted that in addition to the economies effected by the use of a common translating device for the three functions, other economies are effected on account of the particular relation of portions of the circuits related to the device. For example, a portion of the feedback path is used in common for that purpose, for transmitting the demodulated low frequencies, and for providing a path for the space current from source 12. This considerably simplifies the circuits by elimination of details otherwise required for relating these circuits to the anodes of the tubes. Also it should be noted that when the balanced tube arrangement is used for modulation, the modulating wave is impressed differentially on the grids and the resultant modulated wave is similarly derived differentially from the anodes while, when the same tubes are used for demodulation, the common portions of the grid-cathode and anode-cathode circuits are correspondingly used. This means that the balancing arrangements which insure carrier suppression during the modulating operation are also utilized to insure that the input and output circuits are balanced with respect to the incoming side bands so that these side band currents cannot flow in the low frequency circuit 2 or be transmitted without demodulation to the output circuit connected to the secondary of transformer 9. Although a common translating device is used for the modulating and demodulating functions the circuits as a whole which are used for these respective functions are therefore effectively distinct and individual. This relation of the circuits obviates the necessity for the use of low pass filters in circuit 2 or somewhere in the system between circuit 2 and circuit 15.

Fig. 3 illustrates a circuit that can be used alternatively to that of Fig. 2 in the system of Fig. 1. This circuit differs principally from the circuit of Fig. 2 in that the translating device is not self-oscillatory, a separate local carrier source being used. Only so much of the circuit of Fig. 3 as differs materially from that of Fig. 2 will be described in detail. The portions of the circuit which are functionally similar to the corresponding portions of the circuit of Fig. 2 are correspondingly labeled.

The carrier frequency used for modulation and demodulation is supplied from source 19. The circuit 20 which supplies the carrier from source 19 is connected to the opposite terminals of resistance 21 which is included in the common portions of the grid circuits. The incoming side band currents are supplied to these common portions through the same circuit. Hybrid coil 22 renders circuit 15 and source 19 conjugate to each other with respect to the common circuit 20 and therefore insures that carrier and side band currents can be impressed in common on the translating device, but are otherwise confined to their individual circuits. The design and function of such hybrid coil arrangements are now well understood in the art on account of their common use in repeater circuit arrangements. If this, or an equivalent arrangement, were not used, carrier current would, to some extent, be transmitted through the receiving high pass filter shown in Fig. 1, to the transmission line 1, since these receiving filters can discriminate between the carrier and its side band only with difficulty. This would be particularly true at the station where the incoming side bands are of the type $p \pm q$. At the other station, where the incoming side bands would be of the type $2p \pm q$, the filters would ordinarily be adequate to suppress the currents of the frequency p . In the circuit of Fig. 3 the space current for the two tubes, instead of flowing through the circuit carrying the demodulated low frequency, as in Fig. 2, are directly impressed on the primary of transformer 9 through the primary winding 23 of transformer 24 which is used for coupling the common portion of the anode circuits to low frequency circuit 8. This means is alternative to the corresponding means of Fig. 2 and the two expedients are equally applicable to the arrangements of Figs. 2 and 3.

While the invention has been illustrated as embodied in a limited number of forms it will be understood that it is equally applicable to other forms and to variations in details of the form illustrated without departing from the spirit of the invention as defined in appended claims.

In the claims a "pure" modulated wave is a modulated wave which contains no unmodulated component. It may consist of one or both side bands.

What is claimed is:

1. A two-way single-channel carrier wave signaling system, characterized by having a common means at one station for generating and transmitting a carrier modulated wave having a fixed frequency characteristic of frequency p and for demodulating incoming carrier waves comprising single side band components exclusively and having a

fixed frequency characteristic of frequency 65
 $2p$ to reproduce the signal.

2. A two-way single-channel carrier wave signaling system, comprising a common means at one station for generating and transmitting a carrier modulated wave having a fixed frequency characteristic of frequency $2p$ and for demodulating incoming carrier waves comprising single side band components exclusively and having a fixed frequency characteristic of frequency p to reproduce the signal.

3. A two-way single-channel carrier wave signaling system, comprising a common means at one station for generating and transmitting a carrier modulated wave having a fixed frequency characteristic of frequency p and for demodulating incoming carrier modulated waves comprising single side band components exclusively and having a fixed frequency characteristic of frequency 85
 $2p$ to reproduce the signal, and a common means at the other station for correspondingly generating and transmitting a carrier modulated wave having a fixed frequency characteristic of frequency $2p$ and for demodulating the incoming carrier modulated waves having a fixed frequency characteristic of frequency p to reproduce the signal.

4. A two-way single channel carrier wave signaling system comprising means for generating and transmitting in one direction carrier modulated waves comprising single side band components exclusively and having a fixed frequency characteristic of frequency m , means for generating and transmitting in the other direction carrier modulated waves comprising single side band components exclusively having a fixed frequency characteristic of frequency n , the frequencies m and n having a commensurable relation, characterized by an oscillator-modulator-demodulator means at each terminal, common to both directions of transmission.

5. A multiplex carrier wave signaling system, comprising means for generating and transmitting in one direction a plurality of modulated waves, each having frequencies of the type $p \pm q$ and each having a different frequency p , and means for generating and transmitting in the other direction modulated waves, each having frequencies of the type $2p \pm q$, in which the values of p of the different waves is the same as for the waves transmitted in the opposite direction, the frequencies of the waves transmitted in each direction taken together being comprised within a continuous individual range.

6. A two-way single-channel carrier wave signaling system comprising at each station a source of modulating waves and a self-oscillatory modulator-demodulator device comprising a single pair of electric discharge devices for generating and transmit-

ting a pure modulated wave and for demodulating a pure modulated wave incoming from the other to reproduce the modulating wave, the device at one station being adapted to generate a modulated wave the frequency of whose fixed frequency characteristic is p and the device at the other station being adapted to generate a modulated wave the frequency of whose fixed frequency characteristic is $2p$.

7. A multiplex carrier wave signaling system, comprising means at each station for generating and transmitting α pure modulated waves and for demodulating α pure modulated waves, the frequency of each of the fixed frequency characteristics of the 2α transmissions being different from each of the others, said means at each station comprising α sources of locally generated high frequency waves.

8. A multiplex carrier wave signaling system, comprising means at each station for generating and transmitting α pure modulated waves and for demodulating α pure modulated waves, the frequency of each of the fixed frequency characteristics of the 2α transmissions being different from each of the others, said means at each station comprising α functionally independent devices adapted to be used in common for generating and transmitting a modulated wave and for demodulating an incoming modulated wave.

9. A multiplex carrier wave signaling system comprising means at each station for generating and transmitting α pure modulated waves and for demodulating α pure modulated waves, the frequency of each of the fixed frequency characteristics of the 2α transmissions being different from each of the others, said means at each station comprising for each pair of transmitted and received waves, a common high frequency generating, modulating and demodulating means.

10. A multiplex carrier wave signaling system, comprising means for generating and transmitting in one direction a plurality of modulated waves, each having the frequencies $p \pm q$ and in which the carrier frequency differs for each one-way channel, means for generating and transmitting in the other direction modulated waves each having frequencies $2p \pm q$, in which p has the same value as for the opposite direction of transmission, the frequencies of the waves transmitted in each direction taken together being comprised within a continuous individual range, each said signaling channel comprising at each station a common source of waves having the appropriate frequency p for modulating the wave of frequency q for outgoing transmission and for demodulating the incoming modulated waves to reproduce the wave of frequency q .

11. The system of claim 10, in which each signaling channel circuit comprises a common translating device adapted to function jointly as an oscillator-modulator, and demodulator.

12. The system of claim 10, in which the modulated waves transmitted in one direction have frequencies $p - q$ and in which the modulated waves transmitted in the other direction have frequencies $2p + q$.

13. A three-channel system of claim 10, in which frequencies transmitted in one direction are substantially $7,000 - q$, $10,000 - q$ and $13,000 - q$ cycles, and in which the frequencies transmitted in the other direction are substantially $14,000 + q$, $20,000 + q$ and $26,000 + q$ cycles.

14. The system of claim 10 in which each single-channel circuit comprises a common translating device adapted to function jointly as a local carrier oscillator, modulator, and demodulator, in which the frequencies transmitted in one direction are substantially $7,000 - q$, $10,000 - q$ and $13,000 - q$ cycles, and in which the frequencies transmitted in the other direction are substantially $14,000 + q$, $20,000 + q$ and $26,000 + q$ cycles.

15. A combined balanced-modulator-demodulator, comprising in combination a pair of electric discharge translating devices, each having a cathode, an anode, and a controlling element, means associating the cathode-controlling element circuits including a common portion and a portion individual to each controlling element, means associating the cathode-anode circuits including a common portion and a portion individual to each anode, the impedance constants of the devices and of the two associating means being such that the controlling elements and the anodes are each balanced with respect to currents impressed on the common cathode-controlling element portion, means for impressing modulating current in opposite phase on the individual cathode-controlling element portion, means for impressing carrier current on the common cathode-controlling element portion, means for deriving modulated currents from the individual portions of the cathode-anode circuits, means for impressing incoming modulated currents on the common cathode-controlling element portion, means for deriving demodulated low frequency currents from the common cathode-anode portion, and balanced means for relating said carrier and modulated circuit impressing means whereby each may function with respect to the impressed circuit independently of the other.

In witness whereof, I hereunto subscribe my name this 28th day of October A. D., 1924.

JACOB S. JAMMER.
